WILLIAM A. TROUT, OF LOS ANGELES, CALIFORNIA, ASSIGNOR OF ONE-THIRD TO CHESTER A. RASMUSSEN AND ONE-THIRD TO CHARLES R. BUTLER, BOTH OF LONG BEACH, CALIFORNIA.

CASING CLAMP.

Application filed October 15, 1923. Serial No. 668,698.

To all whom it may concern:

Be it known that I, WILLIAM A. TROUT, a citizen of the United States, residing at Los Angeles, in the county of Los Angeles and State of California, have invented new and useful Improvements in Casing Clamps, of which the following is a specification.

This invention relates to casing clamps, and contemplates an improvement over application for casing clamps filed April 11, 1922, in the United States Patent Office, Serial No. 551,465, in the names of myself and Charles R. Butler. The general nature, purpose and object of this casing clamp is the same as the casing clamp referred to in the above mentioned application, with several improvements in the method of assembling said casing clamp to tubing.

An object of the present invention is to provide a casing clamp which is readily adjustable upon tubing and whereby the tubing may be placed in tension when the exact amount of pull upon such tubing has been ascertained. In carrying out the above object it may be stated that it is ordinary practice to couple up strings of casing or tubing by what is known as a clamp, there being a clamp between each string and they are arranged in spaced series at intervals where they join lengths of tubing or casing of different diameters. These clamps consist of rings carrying gaskets, and it often happens that disastrous gas blow-outs occur in an oil well hole, for the reason that a slight lifting of the casing will lift one of the clamps from the gasket and allow gas to escape. It often happens that the gas pressure is extensive enough to badly twist, warp and tear the casing, and in some instances lift it entirely from the well hole. In the pending application, as well as in this application there is illustrated and described a method of localizing the casing clamps to prevent gas blow-out and to so arrange the clamps that the gaskets are not maintained in position between such clamps by the weight of casing or tubing alone. All of the casing or tubing is brought to a given zone where it is joined with the clamp members, which clamp members are inter-associated

so that any blow-out from one casing will be trapped by the confines of the next casing, and I likewise provide relief ports in the clamp members carrying suitable conduits or tubes for conveying away the gas. Regardless of the type of clamp used it is necessary to place the various strings of casing under tension for the reason that certain portions of the casing will of necessity be resting on the bottom of the well hole and portions thereof may sag against the well hole, and to overcome this sag the well operator must exert a certain tension upon the casing, that is, lift the same up, so that the sag will be eliminated. This is a very delicate operation, and if the inside string of casing should happen to be stuck in the mud, which is often the case, the well operator is liable to pull the casing in two if he exerts too much tension upon it. In the type of casing shown in the pending application above referred to, a long thread is used on one of the strings of casing so that the casing may be drawn in tension with one of the spool members screwed down upon the same to the desired point where it will cooperate with a second spool member or clamp, whereupon the casing is cut off at the desired point. Certain other clamps now on the market require a cutting of the casing. However, as this cutting often is done with an acetylene torch the operation is dangerous, particularly if any gas should happen to be flowing upwardly in the casing or between the casing.

In the present invention I do away with the necessity of providing a long thread in order to draw up the casing but so arrange the parts, members and features that the precise length of casing to be cut off may be ascertained and such cutting operation may take place exterior the well hole so that there is no chance of explosion resultant upon cutting pipe by a torch in a well hole, and furthermore, the operation is more positive and exact, as it gives more room for accurate work, than where it is necessary to work at the well hole.

With the above and other objects in view, the invention consists in the novel and useful provision, formation, construction, asso-

ciation and relative arrangement of parts, members and features, all as illustrated in one embodiment in the accompanying drawing, described generally and finally pointed out in claims.

In the drawing:

Figure 1 is a fragmentary view of my improved clamp in association with casing;

Figure 2 is a view on an enlarged scale, 10 partly fragmentary and in section, illustrating features of the clamp and the method of joining tubing or casing therewith; and,

Figure 3 is a fragmentary plan view of 15 certain features of the invention, taken on the line 3—3 of Figure 2, and looking in the direction of the appended arrows.

Referring with particularity to the drawing: The casing clamp is designated as an entirety and in one embodiment by A, of 20 which the flanged base ring a, tube suspending spool b and the cap ring c are elements or members thereof. In the form of casing clamp shown, concentric strings of casing, such as shown in Figure 1 and designated as 25 d, e and f, are adapted to be brought to what may be termed a localized zone and there associated with the casing clamp A. The purpose being to prevent gas blow-outs, inasmuch as it is necessary in case of breakage 30 of one of the casing members or tubing members to burst all of the concentric casing or tubing members in order to have a gas blow-out.

As has been pointed out, it is extremely 35 difficult to place certain of the casings in tension, and likewise, if there is excessive tension on one of the members it is liable to be pulled in two. In the copending application referred to, the tubing or casing e in 40 the showing of this application, was provided with a long thread and had screw threaded engagement with the spool member b. After the tubing or casing e had been drawn upwardly a sufficient distance so that 45 the same would not sag in the well hole, the casing was cut off as has been described. This cutting of the casing or tubing is very 50 difficult of accomplishment and with the present device the casing or tubing is indirectly associated with the element b of the casing clamp A. The element b is termed the spool member, inasmuch as it is provided with two flanges, 1 and 2, projecting from a body portion 3, the body portion being annular in formation. The first string of casing 55 is associated with the first element a by flaring the mouth of the casing, as shown at 4, the element a being formed with a flange 5 which is provided with an annular recess 6 or groove 6 for accommodating the flare 4, and the said element a being likewise provided with a body portion 7 adapted to encompass a portion of the casing f as shown 60 at 8. This method of associating casing with the element a was described in the co-pend-

ing application referred to above. The flange 5 of the element a is formed with one or more annular grooves on a face thereof, as shown at 9 and 10, and within such grooves are placed annular gaskets or washers 11 and 12, the said washers projecting above the face of such flange. The inner surface of the body portion 3 of element b is formed with a taper thread 13, and a union sleeve or collar g has its exterior surface screw threaded as shown at 14 for engagement with the screw threads 13. The said union is likewise provided with taper threads 15 and 16 on its inner surface. It will be noted that the taper threads 15 taper upwardly and outwardly from a common zone 17 of such union, and that the threads 16 taper from such common zone 17 downwardly and outwardly.

It is customary in well casing to have what is called stands of casing, each stand being of a certain length and joined with the next stand by some union or coupling, such as shown at h. Assume now that the first string of casing f is within a cellar j beneath a well derrick flooring k, and it is desired to place the second element b upon the element a of the clamp with the concentric tubing e therein. To do so it is necessary to determine the proper length of the casing e and to cut it off at the proper distance so that it will be placed in tension and practically have little or no sag within the casing f. I therefore associate the casing e with a casing m of the same diameter as the casing e, through the medium of the union or coupling g, the casing m being formed with taper screw threads 18 in screw threaded engagement with the threads 15. The casing m is then drawn upwardly through the medium of an elevator until it is determined that there is no sag in the casing e. It may then be determined how much of the casing e must be cut off and screw threaded so as to be carried by the clamp element b. The casing e is then marked and by turning the casing m associated with the casing e through the medium of the coupling g, the casing e may be unscrewed from the coupling or union h and removed from the well hole to a place where it may be cut off and screw threaded. After it is cut off and screw threaded, and assuming now that its appearance is such as shown by the screw threads 19, it is again connected with the union or coupling g and through such union with the pipe m, this time the element b being held so that the casing m may move therethrough. The casing m is then turned 110 in the proper direction to again screw the casing e to the coupling or union h, whereupon the casing is then put in tension so as not to sag. When the proper tension is determined, the element b is then screwed upon the threads 14 of the union or coupling 115 120 125 130

g, similarly to that shown in Figure 2. It will be noted that the surface 20 of the flange 1 will now bear against the projecting faces of the gaskets 11 and 12. The flanges 5 1 and 5 are formed with a series of aligned bores 21 and 22, through which bolts 23 are passed, which bolts are provided with nuts 24 whereby the elements *a* and *b* may be locked together. As the threads 15 and 10 14 are oppositely disposed, that is, both being right or left, a turning of the casing *m* may now unscrew the same from the union *g* without in any manner disturbing the casing *e* or unscrewing the union from the element 15 *b*, and the casing *m* may then be withdrawn from the element *b*. It will now be observed that the casing *e* is associated with the element *b* through the medium of the union or coupling *g*. The body portion 3 of the element 20 *b* is provided with ports 25 and 26 and with screw threaded openings 27 and 28 communicating with such ports from exterior of the body portion 3. The port 25 will permit communication with the interior of 25 the casing *f*. In the showing of Figure 1, the casing *d* is associated with an element *c* of the clamp, which is similar to the element *a* with the possible exception that it may or may not have the cut away portion 6 adapted 30 to accommodate a flared end of the casing *d*. It is intended, however, that the element *c* should rest upon the flange 2 of the element *b* and against gaskets 29 and 30 carried in annular grooves in the top surface 35 of the flange 2, and that said element *c* should be bolted to the flange 2, such elements *c* and *b* being provided with aligned bores 31 through which bolts 32 are passed for locking the flanges of such elements 40 together. In this case the port 26 would communicate with the interior of the casing *e*. It follows that any number of clamp elements may be provided, depending on the number of concentric strings of casing. It is 45 understood, of course, that the casings are arranged in concentric vertical series. Pipes 33 and 34 communicate with the ports 25 and 26, respectively, by the said pipes being screw threaded for engagement with the 50 screw threaded openings 27 and 28, respectively. These pipes may in turn be led to the atmosphere or tanks where any gas flowing from between said casings may be trapped. A series of unions or couplings *g* 55 may be provided for other strings of casing if desired, where there are a great number of such strings.

The particular device renders it an easy matter to remove casing, to adjust casing 60 as to the tension to be exerted upon same, and likewise the particular device gives assurance that there will be practically no gas blow-out. In present practice excessive gas pressure upon a casing may lift the same

and allow gas to escape over the gaskets, for 65 the reason that it is customary for the casing to hold the clamp down upon the gasket. The present method of associating casing with the clamp and to associate the elements of the clamp so that the gasket members are 70 maintained in a definite position within such clamp in such a manner that the different elements of the clamp cannot be lifted from the gasket or gaskets, gives further assurance that gas blow-outs cannot happen due 75 to failure of the gaskets, for the reason that the casing is independent of the gaskets.

It is obvious that various changes and modifications may be made in practicing the invention, in departure from the particular 80 showing and description as given, without departing from the true spirit of the invention.

Having thus disclosed my invention, I 85 claim and desire to secure by Letters Patent:

1. A well construction for removing tube slack and supporting a plurality of concentric tubes comprising an internally threaded tubing suspension member, and an internally and externally threaded bushing adapted to be fitted at its lower end to a tube, and to receive in its upper end a lifting tube which is adapted to bring the externally threaded portion of the bushing into engagement with the internally threaded tubing suspension member. 90

2. A well construction including in combination with an outer casing, an abutment carried by said outer casing, a string of tubing within said outer casing, a bushing having interior threads and exterior threads and adapted to be carried by an upper section of tubing whereby it may be lowered 100 into the outer casing to engage with the threads of the interior tubing string to permit the entire tubing string to be elevated to remove the slack from the string, and a tubing suspension member having a bore provided with interior threads applied to said upper section of tubing before it is connected with the string of tubing within the outer casing whereby after the tubing has been elevated to remove the slack the tubing suspension member may be threaded 110 on to the exteriorly threaded portion of the bushing, and means for forming a gas tight joint between the tubing suspension member and the abutment carried by an outer casing section. 115

3. A well construction for taking the slack out of tubing strings and suspending the same in position, comprising tubing engaging members having bores of different diameter and provided with external offset flange portions, means for forming a gas tight joint between said flange portions, and the bores of said members being inter- 125

- nally threaded, a member double-threaded interiorly and also provided with external threads whereby adjacent tubing sections may be connected by the internal double threaded portion of said member and then the external threaded portion of said member may be connected with the interior threads of the bore of one of said tubing engaging members.
- 10 4. A well construction for supporting a plurality of concentric tubing strings comprising a plurality of tubing engaging members each having an interior bore provided with threads and also having exterior offset portions adapted to receive fastenings, means for forming a gas tight joint between the abutting faces of said members, and a threaded bushing having interior threads for engaging with a tubing section and exterior threads for engaging with the interior-
- 5 5. A well construction for supporting a plurality of concentric tubing strings including a tubing suspension member having external offset flanges and also having an internal bore provided with threads, packing means for forming a gas tight joint between the abutting flanges of the tubing suspension members, a bushing having interior threads for engaging with the threads of the tubing, and also having exterior threads for engaging with the interiorly threaded portion of the tubing suspension member, and means for fastening the flanges of one member to the flanges of an adjacent member.
- 15 30 In testimony whereof, I have signed my name to this specification.
- 20 35 WILLIAM A. TROUT.
